COOKING RANGE

Ben Valjean, Lansing, Mich., assignor to Motor
Wheel Corporation, Lansing, Mich., a corpo-
ration of Michigan

Application January 21, 1932, Serial No. 587,855

2 Claims. (Cl. 126—44)

The present invention has for its object the efficient utilization of the thermal units of the fuel consumed in combustion chambers of other than symmetrical form, as typified in cooking ranges where the heat is desired to be applied primarily to the top plates of the stove in its passage directly to the flue or indirectly beneath and around the oven for heating the latter.

In stoves of the range type difficulty is encountered in heating the top plates with any degree of uniformity, that portion above the fire box being subjected to much greater heat which diminishes markedly towards the rear; which difficulty is overcome by the present invention wherein the combustion is progressive and prolonged as the burning vapors travel towards the rear, distributing the flames throughout an area including the whole of the passageway over the oven and beneath the top plates. This placement of the combustion over a desired area is attained by the same principle set out in my companion application, Serial No. 587,856 in connection with heaters generally, and particularly those employing a fairly symmetrical combustion chamber usually of the vertical cylindrical type.

While the invention is applicable to heaters using solid fuel such as coal and coke, it is particularly adapted to fluid fuels such as oil or gas, and it is hereinafter set forth in connection with the burning of a liquid fuel such as oil for example.

For a complete understanding of the principle of operation of the heater herein shown reference is made to my Patents Nos. 1,280,596 of October 1, 1918, and 1,639,202, of April 16, 1927; however, as therein set forth the secondary air supply was through an air gap at the neck of the carburetor prior to discharge in the combustion chamber and in a direction transverse to the passage of a premixture of hydrocarbon and air therethrough so that combustion was effected at the entrance to the combustion chamber, whereas in the present form of construction and method of operation the premixture is introduced as such into the combustion chamber and there burned upon admixture with a secondary air supply at selected points and throughout a predetermined area.

While at the stage of low fire, either when the heater is first ignited or when it is permitted to die down, there will naturally exist combustion within the carburetor itself as the hydrocarbon vapors generated are more nearly balanced with the inlet of primary air for complete combustion, but as the generation of the hydrocarbon vapors

increases with the addition of fuel and the increase of heat, the carburetor becomes substantially completely filled with a non-explosive premixture of hydrocarbon vapors and air. This premixture flows into the combustion chamber where complete and progressive combustion ensues as the carbureted mixture or composite vapors are drawn into the secondary air streams, the vapors burning in an atmosphere of air rather than air burning in an atmosphere of vapor.

In order that the invention may be readily understood in terms of apparatus adapted for the practice of the same, a typical cooking range embodying the invention is set forth in the accompanying drawing to serve as a basis for the following description and claims.

In the drawing Fig. 1 is a vertical longitudinal section through a range on the line 1—1 of Fig. 2, and Fig. 2 is a horizontal section and top plan view on the line 2—2 of Fig. 1.

In the drawing is shown a cooking range comprising end walls 11, the base 12, side walls 13 and removable top plates 14, 15, and 16. The oven 17 is contained within the walls of the range proper and spaced therefrom above to provide an upper horizontal space 18, a vertical space 19 and a lower horizontal space 20. The space 18 communicates directly with the flue by means of an opening 21 controlled by the damper 22 slidably adjustable by means of the handle 23, whereby the products of combustion may escape directly in any desired proportion to the flue 24 according as the damper 22 is opened to a greater or less extent. The space 18 also communicates by the vertical space 19 and the lower horizontal space 20 with the flue through the opening 25, whereby a greater or less proportion of the heat may be caused to traverse an indirect path to the flue around the oven 17. This far described, the range is of typical construction adapted for primarily heating the top plates of the range for cooking thereon or causing a portion of the heat to pass around and beneath the oven for baking purposes.

That portion of the range structure ordinarily occupied by the fire box at the front is here divided by a partition 26, the space above the partition forming a vertical leg 27 of what is herein termed the combustion chamber consisting of the vertical space 27 and the horizontal space 18, the combustion chamber being in vertical longitudinal section substantially L-shaped.

The partition 26 is provided with a central opening 28 through which communication is

established with the combustion chamber from a carburetor or premixing device 29, suspended from the partition 26 by means of the bolts 30, of bowl shape with apertures 31 of substantially uniform size and spacing formed in a wall thereof for the admission thereto of primary air. An oil line 32 supplies fuel to the bottom of the carburetor as indicated at 33. The quantity of fuel supplied to the carburetor through the line 32 is controlled by a conventional valve, not shown. A baffle 34 may be employed for facilitating the mixture in the combustion chamber with the composite vapors from the carburetor of secondary air introduced from below through the apertures 35 and 36 to the combustion chamber laterally of the entering premixture remote therefrom and also through the apertures 37-38 to that portion of the combustion chamber more remote from the entering premixture. The top plates 14, 15, and 16 are designedly joined in such manner that narrow spaces are left between their meeting edges whereby secondary air may enter as indicated at 39, 40, 41, and 42 in thin sheets extending transversely of the range top above the combustion chamber. This may be effected by providing the top plates 15 and 16 with offset flanges 15a and 16a and the end walls 11 with offset flanges 11a.

Generally speaking, the operation is as follows: oil delivered to the bottom of the carburetor is there ignited forming hydrocarbon vapors into which jets of primary air through the apertures 31 are discharged to support preliminary combustion within the carburetor. The generation of vapors is increased by the heat deflected downwardly by the overhanging top wall of the burner and eventually from the top plate 14 of the range. As generation of hydrocarbon vapors increases with the addition of fuel and increasing heat, the extent to which combustion takes place within the burner diminishes, the jets of primary air added to the hydrocarbon vapors, bringing about the formation of a premixture of hydro-carbon vapors and air within the carburetor.

A premixture of hydrocarbon vapors and air thus formed passes upward into the space 27 of the combustion chamber, the passage from the carburetor being constricted and interfering down currents being prevented by such constriction and by the baffle 34. The composite vapors of the premixture entering the space 27 are seized upon by the streams of secondary air entering at 35, 36 to be drawn laterally and by the streams of secondary air entering the space at 37-38 and mixes therewith for perfecting combustion throughout the space 27 rather than at the entrance of the composite vapors from the carburetor.

Typically, complete combustion begins above the partition 26 where the composite vapors of the premixture nearest are drawn into the streams of secondary air from the openings 35, 36, 37, 38, producing flames filling the side ends

and top of the space 27 and thence traveling in a horizontal direction through the space 27 and the unconsumed composite vapors from the carburetor travel horizontally through the space 18, secondary air streams entering at 11a, 15a, and 16a seize upon and mingle with these vapors, progressively producing complete combustion; whereby combustion is uniformly distributed in the space 18 beneath the top plates 14, 15, and 16.

If it be desired primarily to heat the top plate 14 to the virtual exclusion of the remainder of the range, the slide damper 22 may be opened and the products of combustion permitted to escape directly to the flue. If, however, it is desired to heat the top of the range more uniformly, the slide damper 22 will be so adjusted that but little of the products of combustion escape directly to the flue through the opening 21 and the remainder will be caused to travel throughout the space 18, the space 19 and the space 20 to the opening 25, heating the oven in a moderate degree. If it be desired to heat the oven for baking purposes, the slide damper 22 will be adjusted to close the opening 21 and all of the products of combustion forced to travel in a circuitous path around and beneath the oven.

The foregoing is but an example of a typical heating apparatus having a non-cylindrical combustion chamber, illustrating the introduction thereto of secondary air in relation to the entrance from the carburetor of the composite vapors formed therein and the portion of the device to be heated. The relative arrangement will be modified to suit the conditions present and the results to be attained, depending upon the desired placement of the area of combustion and the course of travel which it may be desired to have the flames pursue. These conditions would vary with the extent of the combustion chamber, its lateral dimensions, its shape, the direct and indirect paths to be traveled by the products of combustion, etc. In all circumstances the same principle is involved, the complete combustion of the vapors from the fuel being effected in the desired area according as the streams of secondary air are related to the composite vapors entering from the carburetor and traveling through the combustion chamber.

I claim:

1. Combustion apparatus of the range type comprising a combustion chamber having an upper horizontal wall formed of a plurality of heating plates spaced apart to provide a plurality of elongated air inlet slots extending transversely of the longitudinal axis of the apparatus.

2. Combustion apparatus of the range type including a top wall comprising removable heating plates, supporting ledges for said plates, and slots extending transversely of the longitudinal axis of the apparatus, said slots being located at the joints of the removable plates and their supporting ledges.

BEN VALJEAN.
